UNITED STATES PATENT OFFICE.

DAVID HALL RICE, OF LOWELL, MASSACHUSETTS.

CASH-CARRYING APPARATUS.

SPECIFICATION forming part of Letters Patent No. 314,264, dated March 24, 1885.

Application filed February 2, 1885. (No model.)

To all whom it may concern:

Be it known that I, DAVID HALL RICE, of Lowell, in the county of Middlesex and State of Massachusetts, have invented a new and 5 useful Improvement in Systems for Cash-Carriers, of which the following is a specification.

My improvement relates to the system for cash-carriers for which I made application for Letters Patent January 20, 1885, Serial 10 No. 153,400; and it consists in certain novel arrangements and combinations of the several parts thereof, substantially as hereinafter described and claimed.

In the drawings, Figure 1 is a side view of 15 a track and elevator for placing the carrier upon it. Fig. 2 is an enlarged side view of a portion of the track and the elevator with the carrier therein in the act of being placed upon the track. Fig. 3 is an end view of the same 20 upon the section-line A B of Fig. 2. Fig. 4 is another end view from the same position, with the elevator still further raised in the operation of putting the carrier on the track. Fig. 5 is a side view of the track with a carrier-delivery attachment substantially like 25 that of my said former application, and a combination of baskets arranged to receive the carrier as it falls through the drop and deliver it to the attendant below. Fig. 6 30 is an end view of Fig. 5 upon the section-line C D on the latter. Fig. 7 is a side view of a retarding device to separate the balls upon the track and prevent their rolling against or too near each other on the track. Fig. 8 35 is an end view of the track and carrier upon the section-line A' B' of Fig. 7. Fig. 9 is a side view of my improved carrier adapted to traverse the track. Fig. 10 is a vertical transverse section of the same. Fig. 11 is a 40 side view of the removable cup which receives the cash. Fig. 12 is a front end view of the same. Fig. 13 is a view of the hook which is used to withdraw the cup from the carrier to remove or replace the cash therein.

45 A² is the track, which is suspended from the ceiling by rods a a. These rods are attached to frames a' a', which sustain the track rails a² a² and the side braces, a³ a³. In two of the frames a' are made sockets, in which the pivots a⁴ a⁴ are fitted to turn freely; and to these pivots are attached two sections, a⁵ a⁵, of the

rails a² a² by short arms, so as to render the sections capable of either being brought in line with the rails a² a² or of being swung around out of the way upon said pivots, as described in my 55 said former application. In the present instance these rail-sections a⁵ a⁵ are allowed to swing freely upward, and are sustained in line with the rails a² a² by brackets a⁶ a⁶, attached to the frames a' a'. 60

C is the carrier, which is cylindrical, and has the treads c c of its wheels c² c² made to fit and travel on the rails a² a².

An elevator, E, is placed directly beneath the pivoted rail-sections a⁵ a⁵. This elevator 65 consists of the fixed upright rod e, on which travels freely up and down the sleeve e'. This sleeve carries the short arm e², which in turn supports the upright e³ and its attached platform e⁴. This platform is hollowed or dished 70 out to receive the carrier and sustain it in a position to bring its wheel-treads c c directly under the rail-sections a⁵ a⁵ as the elevator rises. These rail-sections should be made 75 broad enough upon their lower faces to prevent the wheel-treads from overlapping and catching upon them as the elevator is raised, which may be accomplished by extending such lower faces outward toward the pivots or toward a line through the centers of the latter. 80

The platform e⁴ of the elevator may be raised by a cord attached to the sleeve e' and pulley overhead, or by the downward extension of the upright e³, or in any other suitable manner. The carrier being placed in it, as shown 85 in Figs. 2, 3, and 4, it is hoisted directly up, and the rail-sections a⁵ a⁵ turn out of the way to allow the carrier and platform to pass between them. When the carrier-wheel-treads have passed upward from the position shown 90 in Fig. 2 and 3 to that of Fig. 4, the rail-sections a⁵ a⁵ drop back to place beneath the treads, and the elevator descends, leaving the carrier on the track, when it rolls off toward the desired station to which it is sent. In order 95 to facilitate the starting of the carrier after being placed upon the rail-sections a⁵ a⁵ by the elevator, I make the pitch or incline of these rail-sections steeper than that of the rails of the track on either side of them. I 100 also attach to the elevator an upright arm behind the carrier e³, which curves upward and

over the periphery of the latter, so as to allow it to be lifted out of the platform e^4 as the elevator descends, and then comes in contact with the back side of the carrier, pushing or 5 starting it along on the track.

In Figs. 5 and 6 is shown an arrangement of baskets at the receiving-station of my track which is simple and effective.

The delivery mechanism of the station is 10 constructed substantially as shown and described in my said former application, and will therefore be easily understood from a brief description.

Two rail-sections, $b^1 b^2$, are hung on pivots 15 $b^3 b^4$, as described for the elevator-sections $a^1 a^2$; but, unlike the latter, they are free to drop downward and outward. They are held in line with the rails $a^1 a^2$ by the lever-hooks $b^5 b^6$, pivoted at $b^7 b^8$, and having their upper arms projecting directly toward each other. Between 20 the ends of these arms a key or wedge, b^9 , is dropped, so as to prevent them from approaching each other and the lower ends of the hooks from escaping from under the pivoted rail-sections $b^1 b^2$. This key slides up and down in the bracket b^6 , and has attached to its lower end the shoe b^5 , so located as to come in contact with the proper carrier-wheel, and thus lift the key up from between the arms of hooks $b^5 b^6$, 25 and hold it up while the carrier passes upon the rail-sections $b^1 b^2$. The pressure of the carrier thus swings the rail-sections away from under it, and these press to each side the hooks $b^5 b^6$, and the carrier drops through between 30 them into the basket d . A light spring, b^7 , compresses the lever-hooks $b^5 b^6$ together again after the carrier has passed through, and brings the rail-sections $b^1 b^2$ back into line with rails $a^1 a^2$ again, when the key b^9 drops in between 35 the upper arms of the lever-hooks and locks them in place. A ring, c^1 , on one of the carrier-wheels is employed to lift key b^9 , and when this ring is so placed as to pass to one side of the shoe b^5 the carrier passes over, as shown 40 in Figs. 5 and 6, without dropping down into the basket d . This basket d is pivoted to an arm at d' , the arm being attached to one of the frames a' , as shown, and the pivot d' being placed far enough down on the side of the 45 basket to cause it to empty itself when allowed to swing freely upon this pivot.

On the opposite sides of the basket d , and near the other end from its pivot, are fastened to its rim eyes $d^3 d^4$, to which cords are fastened, which pass over two small pulleys, $d^2 d^3$, attached to the opposite sides of one of the frames a' . These cords unite into one at some distance below the track, and are fastened to a fixed pin within reach of an attendant below. When the attendant perceives that a carrier has dropped into basket d , he releases these cords, and the basket, being released at that side, turns upon its pivot d' and empties its contents into a second basket, d^4 , hung so 55 as to receive the carrier from the first. This second basket d^4 is suspended by cords on each

side to the ends of a spring-roller, d^5 , extending across the top of frame a' , to which it is attached by a suitable bracket, the cords being wound upon the ends of this roller of 70 sufficient length to allow the basket d^4 when they are unwound, to descend to an attendant beneath. The spring-roller d^5 is of any ordinary and well-known construction, and its spring is strong enough to hold the basket d^4 75 in position under basket d ; but when the carrier is dumped into it out of the latter the added weight will cause it to descend automatically. In the meantime the attendant, by pulling upon the cords passing over pulleys $d^6 d^7$, has restored the basket d to place 80 under the track, ready for another carrier, and by removing the carrier from basket d^4 the latter will automatically ascend to its original position. 85

In Figs. 9, 10, 11, 12, and 13 is shown the improved carrier C, I have devised for use upon the described track and appliances. It consists merely of an axle, c' , and two wheels, $c^1 c^2$, having wheel-threads $c c$ and a flange, c^3 , 90 around one of them. The wheels $c^1 c^2$ each revolve independently upon the axle, and the axle is free to revolve by a third and independent movement on the wheels. The axle is made hollow, and large enough to receive 95 the cash or parcel to be carried within it. I thus enable the wheels to move independently in passing around curves in the track, and with no substantial added friction, the independent motion of the axle avoiding this difficulty, and I am also able to make the wheels large and heavy, so as to roll easily upon the track, without thereby adding to the friction upon the axle, as is the case when the weight is added to the body of a common carriage. 100

In order to keep the wheels in place upon the axle, I attach to the ends of the latter flanges $c^4 c^5$, and I have shown a central flange, c^6 , between the wheels, to avoid too great friction between their inner faces; but an annular projection upon one of the latter may be substituted for this middle flange. Each wheel fits loosely between the flanges and around the axle, thus insuring the least friction. The wheels may be made of wood, fiber, leatheroid, or any well-known similar material. 115

The cavity within the axle, owing to the independent rotary motion of the latter, requires no appliances to hold the cash in the middle of it, and the cash or a small bundle 120 may be placed directly in it, or in a drawer or other receptacle, or it may be provided with a suitable cover or covers, as desired; but the attachments I have adapted to it for convenience are as follows: I make of thin 125 metal a cylindrical cup, m , open at one end and closed at the other, and fitted to just slide into the bore of the axle c' . A fixed cap, c^6 , is attached to the axle to close it. Near the open end of the cup m I expand the metal outward slightly, and cut longitudinal slots $m' m'$ 130 a short distance apart through this expanded

portion of the metal. When the cup is pressed into the bore of axle c' , an elastic band is thus formed around it, which, by its pressure upon the inside of the axle, prevents the cup coming out until forcibly withdrawn. To accomplish this and save space, I provide the outer closed end of the cup with a socketed piece, m^2 , having a slot, m^3 , in its outer face and a chamber larger than the slot in at least one direction, and in two directions as I have shown it. I provide a T-shaped hook, m^4 , fitted to be inserted in the slot and turned so as to catch its end under the piece m^2 , when the cup m may be withdrawn. This socketed piece m^2 may be placed inside the cup, and the slot m^3 made through the exposed end of the cup into its chamber, if desired. In order to better insure the retention of the cup in the carrier-axle, I enlarge the bore of the latter where it surrounds the slots m^1 and the enlargement of the cup through which they are cut when the cup is seated in place in the axle.

By this construction of the parts I produce a carrier with smooth faces for passing off of and upon the track, as described, and one which will roll down a comparatively slight incline, and without the aid of devices to give it an impulse, when placed upon the track, as the act of doing this is sure to produce a movement of the axle and wheels upon one another, which starts it rolling.

If the cup m be made of metal, I line it with rubber or felt or some other elastic medium, to prevent the change from rattling in it, or roll the latter in the same before placing it in the cup. The use of a cup open at the end enables the attendant to handle and insert and remove the change very quickly.

It is evident that with my elevator mechanism either the arm e^5 or the greater pitch of the track-sections a^5 alone can be used to assist the starting of the carrier on the track, if desired. It is also evident that one of the wheels c^2 may be rigidly fixed to the hollow axle c' of the carrier C , leaving the other free to revolve thereon, and some of the advantages of this form of carrier be retained; but I prefer the construction before described.

It is found that in many cases carriers will roll along the track, rubbing and striking against each other, and not only injuring the carriers, but interfering with their progress along the track and causing a delivery-section of the track in some instances to be choked or blocked by a second carrier following the one passing through too closely. To avoid all these difficulties I have devised what I term a "retarding device," constructed as follows:

At some place on the track A^2 (see Figs. 7 and 8) I attach to two of the frames a^1 two other frames, n^1 , by means of lugs n^1 , fitted to pins n^2 , on which they are free to play up and down. The frames n^1 are secured rigidly together at top and bottom by bars n^3 , above and below the path of the carriers, so

that they will move together. On top of the bar n^3 , below the carriers, is fixed another bar, n^4 , in such position that the carrier will run onto it and depress the frame n^1 , which is held up by spiral springs on the upper pins, n^2 , under its upper lugs, n^1 . Attached to the upper lug, n^1 , on the end from which the carriers come over the track, is a bar, n^5 , which is so adjusted that when the frame n^1 is raised by the springs it is above the path of the carriers, but when the frame is pressed down by a carrier passing over bar n^4 it is projected into the path of the carriers. The beveled end of bar n^5 , upon which a carrier first runs, is just far enough along down the track from the bar n^5 to cause the latter to descend behind that carrier before it has fully passed from under it. The track at a^{15} , just ahead of the bar n^5 , is also moved with a steeper pitch than other portions, as shown in Fig. 7. When two carriers come along the track close together, as shown, the first one after passing under bar n^5 runs onto bar n^4 , and thus brings down bar n^5 into the path of the following carrier and arrests it until the first has passed off of bar n^4 , when the second carrier will be released and the two will travel over the track separated by the distance between the bar n^5 and the farther end of bar n^4 , and cease to interfere with each other. The steeper pitch of the track at a^{15} assists the second carrier to start when released by the bar.

It is obvious that other forms of connection between bar a^4 and the arresting-bar a^5 may be employed and the two still be made to work in unison; but their relative positions must always be so that they are longitudinally on the track nearer to each other than the diameter of the carrier, in order to enable bar n^5 to enter the space within and between the peripheries of the carriers and arrest the second one.

What I claim as new and of my invention is—

1. In the elevated track A^2 , the combination of the rail-sections a^5 , pivoted on axes substantially parallel to the track, with an elevator mechanism adapted to elevate the carrier-wheels past and above said rail-sections and allow the latter to drop beneath the carrier-wheels, substantially as described.

2. In the elevated track A^2 , in combination with the rails a^2 , the pivoted rail-section a^5 , placed at a steeper pitch or incline than the rails, substantially as described.

3. In the elevated track A^2 , the combination of the pivoted track-sections a^5 , the elevator E , and the curved arm e^5 , attached thereto and adjusted at such a distance from the carrier as to enable it to strike the latter on the rear side as the elevator descends after depositing the carrier upon the track, substantially as described.

4. The combination, in the elevated track A^2 , of the pivoted rail-sections b , the basket d under the track, provided with hinges or

5 pivots allowing it to be reversed, and with devices for reversing the same, substantially as described, and the falling and rising basket d^4 , with elevating and lowering devices attached thereto, substantially as set forth and described.

5. The combination, in the elevated track A^2 , of the pivoted rail-sections $b\ b$, the basket d under the track, provided with hinges or 10 pivots allowing it to be reversed, and with devices for reversing the same, substantially as described, and the automatically falling and rising basket d^4 , with automatic elevating and lowering mechanism attached thereto, substantially as set forth and described.

15 6. In the carrier C, the combination of the hollow axle c' with the wheels $c^2\ c^2$, said hollow axle being adapted to receive and retain the cash therein, substantially as described.

20 7. In the carrier C, the combination of the hollow axle c' , provided with wheel-retaining flanges $c^4\ c^4$ and the wheels $c^2\ c^2$, said hollow axle being adapted to receive and retain the cash therein, substantially as described.

25 8. In the carrier C, the combination of the wheels $c^2\ c^2$, the hollow axle c' , and the cup or receptacle m , fitted to the interior of said axle, substantially as described.

9. In the carrier C, the combination of the hollow axle c' , the wheels $c^2\ c^2$, and the flange c^3 , attached to one of said wheels, substantially as described.

30 10. In the carrier C, the combination of the hollow axle c' , provided with flanges $c^4\ c^4$, the 35 wheels $c^2\ c^2$, and their separating-flange c^3 , substantially as described.

11. In the carrier C, in combination with the axial cavity therein, the cash-cup m , provided with an enlarged annular portion having slots $m'\ m'$ therein, forming springs around said cup 40 adapted to bear against the wall of said cavity, substantially as described.

12. In the carrier C, in combination with the

axial cavity therein, the cup m , provided with the slot m^2 in its exposed end, and a chamber 45 beneath said slot larger than the slot transversely of the latter, substantially as described.

13. In the carrier C, the combination of the wheels $c^2\ c^2$ with the hollow axle c' , the latter having the cavity within it closed at one end 50 and open at the other, substantially as described.

14. In combination with the track A^2 , the bar n^4 , placed in the path of the carrier and adapted to be moved aside by the carrier passing the same, connecting devices substantially as set forth, and the bar n^5 , connected to bar n^4 thereby, and adjusted to be projected within the path of the carrier as the bar n^4 is moved away therefrom at a point behind the latter 60 and within a distance from its center equal to its diameter, substantially as described.

15. In combination with the track A^2 and the carrier C, the retarding-bar n^5 , adapted to move into and out of the path of the carrier, 65 and mechanism, substantially as set forth, automatically operated by the carrier and connected to said bar, adapted to move said bar into the path of the carrier behind it and within a distance from its center equal to its diameter, and to hold said bar in that position while said carrier passes over a predetermined length of said track, and then to automatically withdraw the same, substantially as described.

16. In combination with the track A^2 , made 75 with a steeper pitch or grade than its normal one at a^5 , the bar n^5 , adapted to be projected into the path of the carrier, connected mechanism, substantially as set forth, adapted to be operated by the carrier and so project it, 80 and the carrier C, substantially as described.
